UNITED STATES PATENT OFFICE.

ANDREW THOMA, OF CAMBRIDGE, MASSACHUSETTS, ASSIGNOR TO NORTH AMERICAN CHEMICAL COMPANY, OF NEW YORK, N. Y., A CORPORATION OF MAINE.

APPARATUS FOR FILLING SHOE-BOTTOMS.

1,218,017.

Specification of Letters Patent.

Patented Mar. 6, 1917.

Application filed January 3, 1907. Serial No. 350,588.

To all whom it may concern:

Be it known that I, ANDREW THOMA, a citizen of the United States, and resident of Cambridge, in the county of Middlesex and State of Massachusetts, have invented an Improvement in Apparatus for Filling Shoe-Bottoms, of which the following description, in connection with the accompanying drawings, is a specification, like letters on the drawings representing like parts.

My present invention is a power machine for filling the bottoms of shoes with a normally semi-plastic, tough, elastic, filler, such for example as is disclosed in my Patent No. 832,002 of September 25, 1906. The most common means of applying this kind of filler to shoe bottoms is that shown in United States Patent No. 808,227 of December 26, 1905, which requires that the filler shall be heated in order to render it flowing and plastic, and requires the operator to lift small portions with a spatula, one hand being required for this purpose while the other hand manipulates the shoe. My present invention aims to do away with these objectionable features, leaving the operator at liberty to use both hands in supporting and manipulating the shoe, and doing away with the disagreeable presence of heat, and at the same time affording means for filling shoes with far greater rapidity than is possible by the semi-hand method above referred to. In carrying out my invention I provide mixers which serve to prepare the filler material in a preliminary way, and a friction device, which at the same time is a feeding device which serves to liquefy or render plastic the mass without the presence of extraneous steam pipes or other heating means, a manually controlled delivery by which the operator controls the delivery of the exact amount of filler required for the given shoe-bottom in the hands of the operator, an innersole-lip controlled width governor for governing the width of filler delivery, and a rapidly reciprocating laying device or condensing and compacting smoother and leveler adjacent the delivery device capable of operating with the cold plastic filler in properly embedding the latter under suitable pressure in the shoe-bottom cavity. Various features of my invention are of importance and practical value, apart from the others, all of which will be more defi-

nitely defined in the claims; and the invention will be more fully understood from the following description, taken in connection with the accompanying drawings in which I have illustrated one embodiment of the 60 invention.

In the drawings

Figure 1 is a central vertical sectional view of a machine embodying all features of my invention;

Fig. 2 is an enlarged sectional detail of the delivering device;

Fig. 3 is a transverse sectional view.

For simplicity of presentation and clearness of understanding, I have shown the 70 body of the machine as a single casting 1 containing an upper receptacle 2, a somewhat narrowed receiving chamber 3 and a feed chamber 4 terminating in a delivery or discharge end 5. In the feed chamber I 75 mount means for creating considerable friction with relation to the filler material with which the feed chamber is supplied, and in connection with said friction device I provide means for forcing the filler forward, 80 and also preliminary means for mixing or grinding the filler, thereby supplementing the friction action and feeding movement in getting the filler into proper plastic condition for being deposited in a shoe-bottom. 85 Preferably the mixing and grinding or disintegrating device and the friction device are separate although coöperating, the disintegrating and mixing device being heré indicated at 6 and the friction device at 7, 90 the latter constituting also the feed device, being shown as a worm feed or conical fluted shaft which screws the material forward with considerable resistance and yet is so shaped that it permits more or less slipping of the material, thereby increasing the frictional action on which I depend to a considerable extent for liquefying the filler 95 composition. The disintegrator or mixer 6 has claw members or knives 8 and deflector blades 9, in the machine of the drawings, which engage a body 10 of the filler material in the hopper or receptacle 2, although any other form of device may be employed within my invention for tearing apart and clawing off the filler loaf or body 10 and then commingling and mixing or agitating the fragments, the purpose being to bring about a finely divided and thoroughly mixed 105 condition of the filler so that it will be, to 110

a large extent, in condition for application to the shoe-bottom. As herein shown, the shaft of the friction feed device 7 is provided with fast and loose power pulleys, 12, 5 13 and a driving gear 14 meshing with a pinion 15 on the shaft 16 of the disintegrator and mixer. At the opposite end of the latter shaft I provide a spur gear 17 meshing with a smaller pinion 18 on a shaft 19 provided with a cam wheel 20 for rapidly 10 reciprocating a link 21 extending centrally from a transverse shaft 22, at whose opposite ends are swing rods 23 (only one being herein shown), pivoted at 24 respectively 15 at the opposite sides of the machine and supporting at their lower ends a laying or packing and spreading device 25 for leveling down, condensing, compacting and smoothing or pressing the filler firm into 20 all the crevices of the shoe bottom. This laying device 25 performs the same functions as the super-heating roll of the above mentioned Patent No. 808,227 excepting that it accomplishes my purpose without 25 heat, does not rotate, and smooths or levels down the filler more quickly and accurately, due to its extremely rapid short back-and-forth movement. The back-and-forth movement is so rapid that the succession of short 30 smoothing packing motions causes the filler to be laid or condensed and smoothed and pressed down flat into the shoe-bottom almost perfectly, as the shoe is simply drawn back from the machine in contact with said 35 laying device. While the latter may be prevented from sticking to the filler by heat if desired, or by any other means, I prefer to accomplish the purpose by maintaining the engaging side thereof coated with a thin 40 film of repellent liquid, such as oil or soapy water. As herein shown I have provided a pocket 26 containing a supply 27 of soapy water of a thin jelly-like consistency capable of jarring or oozing through perforations 28 provided for the purpose in the 45 bottom of the pocket 26, so that as the soapy water or other repellent substance oozes or drops through the openings 28 it is scraped or cut off by the adjacent edge of the rapidly 50 moving laying device 25 in sufficient quantity to maintain the under side thereof constantly coated or lubricated with this repellent material. This effectually prevents the filler from sticking to the device 25 55 without interfering with the effective laying function of the latter.

As the subdivided filler material is forced forward by the feed screw 7 toward the delivery end 5 it is preferably compelled to 60 pass through a screen on subdividing plate 29 for rendering the filler still more plastic and free-flowing by the friction of the filler in passing through the holes of the plate. If the filler is not being deposited in a shoe 65 at the moment it passes thence through a

channel 30 back to the rear end of the feed chamber, the idea being to keep the filler in motion and prevent its setting and clogging. By this means I am sure always to get a prompt delivery when required, as the 70 filler is not merely kept in proper condition, by its constant movement, but it is always ready for delivery, whereas if it were permitted to stop there would be a momentary 75 sluggishness to overcome, due to its extremely 80 sticky and compact nature. At the mouth of the delivery end I provide a regulator or filler ejector in the form of a slide 85 31, shown as normally held forward in closing position by a spring 32 and operated by a bell crank 33 and foot lever 34, said slide having a valve-plate or filler actuator 35 in position to close or partially close the channel 30 according as the slide is entirely 90 opened or only partially opened. This plate 35 thus compels the instant deflection of the moving stream of filler material, so that it must deliver under pressure into the shoe-bottom cavity instantly and properly when the slide is opened. In Figs. 2 and 3 I have 95 shown the parts in enlarged detail, where it will be seen that I have provided width-guards 36 whose depending ends 37 engage the stitching ribs 38 of an innersole 39 whose cavity 40 is to be filled. These width guards 95 are yieldingly supported by any suitable means, being herein shown as carried at the lower ends of posts 41 supported at the side of the machine and held constantly against the slide 31 and side notches 42 by springs 100 43 which engage the holding brackets 44 at their lower ends, and pins 45 in the posts 41 at their upper ends. The width guards 36 slide laterally in the lower ends of the posts, being held normally outward by springs 46 105 and compelled to move inwardly by reason of their engagement with the opposite stitch receiving ribs 38. I regard it important to govern the filler delivery with reference to the lips or ribs 38 of the shoe bottom cavity, 110 as there is no other portion of the shoe that can be used as a governing contour to accomplish proper regulation of the area of filler being laid to accord with the area of the cavity. The contour of a shoe at its 115 sides differs from the contour of the innersole and welt, and both differ from the contour of the innersole cavity or bottom cavity, *i. e.* they differ from the contour of the cavity which is bounded by the inner-edge 120 of the lip 38. Hence by providing a control 125 which is governed directly with reference to this lip, the result is that the filler delivery corresponds exactly with the requirements of the cavity. As the cavity varies in width, 125 the controlling devices 36 vary. Also, as these devices are in line with the discharge opening, they are moved in or out, in accordance with the variations of cavity at the very point of filler deposit therein. To in- 130

sure the effectual prevention of escape of material at the side as it is delivered in varying quantities, I make the width guards V-shaped in cross section, as clearly shown in Fig. 2, and provide the V-shaped notches 42 in the opposite sides of the delivery opening for receiving said V-shaped width guards. Thus, when the slide 31 moves back the width guards move upwardly in the notches 42, thereby preventing the escape of any of the filler material at the sides, and compelling the thin flat stream of filler to flow directly into the shoe cavity 40. The width guards and their notches 42 are so arranged that when the operator has engaged the shoe therewith he simply presses upwardly and thereby opens the slide 31. I find that this arrangement gives the operator more confidence than when he regulates the delivery of the filler entirely by his foot. Pressing the shoe upwardly is a natural movement and the operator has no difficulty in learning to regulate the supply in this manner and at the same time pull the shoe forward (as it is being filled) to the laying device 25. When the slide 31 is moved ahead to closed position it pushes the V-shaped guards forward and downwardly until the opening is closed. The guards have considerable lateral length in order to permit them to be moved inwardly by their engagement with the stitch receiving ribs 38 as the shoe is pulled forward toward the narrow toe part. In other words, I make the width guards capable of automatically following the contour of the shoe bottom cavity by the engagement of the hook-shaped ends 37 with the stitch receiving ribs. This operation automatically shapes the ribbon-like flow of filler to correspond exactly to the shape of the shoe bottom cavity. To permit the ready escape of the width guards from the stitch receiving rib when the toe end of the shoe is reached I make the rear side 47 of the hook-shaped end obliquely curved and rounded so that when the toe end of the ribs 38 is reached and the operator quickly closes the slide 31, the width guards simply ride up and across the stitch receiving ribs and permit the shoe to leave without restraint.

In operation, a complement of filler material is placed in the receptacle portion 2 of the machine and is automatically disintegrated and comminuted as the parts rotate in the direction of the arrows. As the mass is disintegrated and drops into the receiving chamber it is continually churned and mixed. Meanwhile the partially prepared filler is fed forcibly forward by the feed worm 7 whose friction serves not only to forward the filler but to further soften it, the final softening thereof being effected and completed by the forcing of the partially softened filler through the screen or perforated diaphragm 29. This screen sub-

divides the filler and puts it in proper shape for filling the shoe. The flow of the filler in the machine is continuous whether the machine is filling shoes or not, the filler in the latter instance passing back through the channel 30, and so on around continuously, always ready to fill a shoe whenever the operator is ready. When ready, the operator with a shoe firmly held in both hands if desired, engages one rib 38 with the adjacent hook 37 and by a quick, deft movement pulls the shoe and said hook over until he catches the opposite hook on the opposite rib. In practice this is accomplished almost instantly and the shoe is simultaneously centered and pushed forward until its shank portion is directly beneath the delivery opening, and that instant the operator raises the shoe up forcibly against the width guards, thereby instantly starting the delivery of filler into the shoe bottom, or depresses the foot treadle, which opens the slide or feed controller exactly the distance required by the operator for the given shoe, the upward movement of the gage or width controllers 36 permitting at the same time the shoe to come close to the delivery opening. As the operator controls the amount of the filler delivered he quickly pulls the shoe toward himself, the width guards simultaneously gaging the width of the filler delivered exactly to the requirements of the shoe, and as the toe of the shoe is reached, the operator closes the slide, or permits it to close under the influence of the spring 32, the width guards at the same time escaping from the shoe, which immediately comes in contact with the rapidly agitated or reciprocated laying device 25 which smooths and compacts the filler into the shoe as desired. All this is accomplished with great rapidity and ease by the operator. There is no fatigue in laying the filler with the laying device, as the operator simply pulls the shoe up against said device with both hands and pulls it straight forward toward himself, the rapid back-and-forth movement of the laying device working the filler down compactly and smoothly and almost imperceptibly.

One of the main advantages of my invention is that it renders it possible to use the filler without melting it by heat, the hot pots, roll, etc., of the previous machine being entirely eliminated. The speed of my present invention is likewise an important feature, as the operator soon learns to gage the delivery rapidly and accurately so that he can fill the shoes as quickly as he can handle them, the movement being merely an in and out movement coupled with the slight initial lateral movement necessary for catching the hook ends of the width guards. The operator not only has both hands to devote to the shoe, but is without

the fatigue and delay of being obliged to select portions of the filler and lift it up into the shoe from the pot as in the above mentioned previous apparatus.

While for convenience I have adapted my machine to the loaf or package form of the filler, I wish it understood that I am not limited thereto, as my invention includes broadly the mixing or churning and preparing of the ingredients to a fairly consistent state for being leveled into a shoe bottom at the time of use, and also embraces broadly the provision of means for mechanically fluidifying or rendering sufficiently plastic a normally stiff filler to permit its being laid in a shoe bottom. My mechanism renders it unnecessary to bring about a state of high fluidity as a more sluggish condition is practicable because of the fact that the machine itself forces the material into a thin layer independently of the exertions of the operator, and the laying device is specially adapted to mold the filler cold. Of course it will be understood that various of the separate elements or features of my invention may be used with the hot process if desired, and that I am not limited in all cases to the relations of parts herein preferred, although one of my chief aims has been to devise means for handling the filler cold and I therefore prefer not to use heat except possibly to start the machine and hasten the melting of the filler at the start. One of the main reasons for having the roll hot in the above mentioned apparatus was to prevent the filler from sticking to the roll; I have found that by providing various kinds of oily or soapy coatings for the roll (or the vibrating device as herein shown), the laying device may be used cold without danger of the filler sticking thereto. The soapy solution is preferable, as oily material is apt to combine with the filler, and, to some extent, neutralize some of the beneficial effects of the latter. I have found the provision of a vibrating, laying motion to be of decided advantage irrespective of whether it is used cold or not, as it materially saves the time and strength of the operator. This laying mechanism and certain other features of my invention not herein claimed, are duly claimed in my divisional Patent No. 1,113,381.

The rubbing and mixing of the integral portions of the hacked filler create a softening of the material akin to heating, but without heat, and the further subdividing and continuous flow through the machine produces a smoother and nicer consistency than is feasible with heat, eliminating all tendency of the heavier ingredients of the composition to settle by gravity at the bottom. This cold process is not only beneficial to the material as to quality in the respects mentioned, but it avoids the extreme lia-

bility of over-heating and spoiling the filler by the previous heating method.

While I prefer for many reasons the forms of feeding mechanism, delivery mechanism, and automatic shaping mechanism or width gaging contained in the machine of the drawings, I am particular to state that I regard my invention as broadly novel in the points mentioned, and I intend this patent to cover any and all forms of mechanical embodiments within the broad idea of means which constitutes my invention.

Having described my invention, what I claim as new and desired to secure by Letters Patent is:

1. A machine for filling shoes, having in combination, a receptacle for filler, and means arranged to be controlled by a contour of the bottom of the shoe for causing said filler to be delivered to and confined within the bottom cavity within the welt thereof.

2. A machine for filling shoes, having in combination, a receptacle for filler, means for causing said filler to be delivered to a shoe within the shoe-bottom cavity thereof, and means governed with reference to the innersole rib for controlling the area to which said filler is delivered in such manner that said area always bears a fixed ratio to the width of the shoe-bottom cavity at each corresponding point throughout its length.

3. A machine for applying filler to the innersoles of shoes, having in combination, a receptacle for filler, and means arranged to be guided by the contour of the innersole cavity for controlling the area to which filler is delivered, said means arranged to become operative upon presentation of a shoe in operative relation to the machine.

4. A machine for filling shoes, comprising mechanism for restricting the delivery of filler to the shoe bottom cavity, and including opposite controlling devices for engaging and following the rim of said cavity.

5. A machine for filling shoes, comprising a receptacle for filler having a delivery orifice, and width-gaging means operative in said orifice and arranged to be actuated by the portion of said shoe which is at said orifice at any given instant, as distinguished from portions of said shoe either forward or rearward from said orifice.

6. A machine for filling shoes, comprising a receptacle for filler having a delivery orifice, and width-gaging means operative for opening and closing said orifice and arranged to control the orifice in such manner that the extent of opening of said orifice always bears a fixed ratio to the width of the shoe bottom cavity at that point thereof which is at the orifice at any given instant.

7. A machine for filling shoes, comprising a receptacle for filler having a delivery orifice, and mechanism for opening and closing

5 said orifice, including means becoming operative upon the presentation of a shoe for moving said mechanism to open position, consisting of devices movable widthwise of the shoe and responsive in position to the variations in width of the shoe bottom cavity to be filled, and so arranged that said devices control the orifice with reference to the width of the shoe bottom cavity at that 10 point thereof which, at any given instant, is at the filler delivery orifice, and in such manner that the delivery of the filler is always restricted to said shoe-bottom cavity.

15 8. A machine for filling shoes, comprising a receptacle for filler having a delivery orifice, and width-gaging means operable to control the amount of filler delivery by varying the pressure of the shoe toward said orifice.

20 9. A machine for filling shoes, comprising a receptacle for filler having a delivery orifice, a valve controlling the flow of filler through said orifice, and means operable by varying the pressure of a shoe toward the 25 orifice for controlling the opening of said valve.

30 10. A machine for handling shoe bottom filler, comprising means for supplying the filler material, said machine containing a delivery opening, means for continuously forcing said material forward to said delivery opening, and mechanism coöperating therewith for delivering intermittently at said opening the filler in a thin narrow 35 ribbon-like layer into the shoe conforming in shape approximately to the thickness and width of a shoe cavity.

40 11. A machine for handling shoe bottom filler, comprising means for supplying the filler material, said machine containing a delivery opening, means for forcing said ma-

terial forward to said delivery opening, and mechanism at the extreme outer end of said opening coöperating therewith for delivering the filler in a thin ribbon-like layer into 45 the shoe conforming in shape approximately to the thickness and width of a shoe cavity.

12. A machine for handling shoe bottom filler, comprising means for mechanically rendering fluid normally semi-solid shoe 50 filler, and delivering means for forcing the fluid filler out in a thin layer conforming approximately to the shoe-cavity.

13. A machine for handling shoe bottom filler, comprising means for mechanically 55 rendering fluid normally semi-solid shoe filler, delivering means for forcing the fluid filler out in a thin layer, and means for automatically conforming the width of said 60 layer to the shape of a shoe bottom.

14. A machine for handling shoe bottom filler, comprising means for mechanically rendering fluid normally semi-solid shoe 65 filler, delivering means under the control of the operator for forcing the filler out in a thin layer, and means for varying the width of said layer as delivered.

15. A machine for handling shoe bottom filler, comprising means for mechanically 70 rendering fluid normally semi-solid shoe filler, delivering means for forcing the filler out in a thin layer, and width guards beyond the delivery opening of the machine for confining said delivered portion to the shoe 75 bottom.

In testimony whereof, I have signed my name to this specification, in the presence of two subscribing witnesses.

ANDREW THOMA.
